Primary Examiner — Michael C Stout*Assistant Examiner* — Melvin L Davis(74) *Attorney, Agent, or Firm* — Faegre Drinker Biddle & Reath LLP(57) **CLAIM**

The ornamental design for an inflatable mermaid tail float, as shown and described.

DESCRIPTION

FIG. 1 is a top perspective view of an inflatable mermaid tail float showing my new design;

FIG. 2 is a top plan view thereof;

FIG. 3 is a bottom plan view thereof;

FIG. 4 is a first side elevational view thereof;

FIG. 5 is a second side elevational view thereof;

FIG. 6 is a third side elevational view thereof; and,

FIG. 7 is a fourth side elevational view thereof.

The broken lines in the drawings depict portions of the inflatable mermaid tail float that form no part of the claimed design.
